UNITED STATES PATENT OFFICE.

CHARLES HENRY LISTER, OF NORTH ST. PAUL, MINNESOTA.

CASTING-MACHINE.

1,230,587.

Specification of Letters Patent.

Patented June 19, 1917.

Application filed June 21, 1915. Serial No. 35,256.

To all whom it may concern:

Be it known that I, CHARLES HENRY LISTER, a citizen of the United States, residing at North St. Paul, in the county of Ramsey and State of Minnesota, have invented new and useful Improvements in Casting-Machines, of which the following is a specification.

My invention relates to improvements in casting machines. It is an improvement upon the machine covered by my patent numbered 1,033,254 and dated, July 23rd, 1912.

Its object is to provide a simple, durable and efficient machine of this class, in which a plurality of separable molds are driven in an endless series, said molds being adapted to be filled with molten metal and designed to be opened to permit the discharge of the molded product, then submerged in water to be cooled and finally closed for refilling.

A further object is to provide in a machine of this kind novel and efficient means for opening and closing the several mold sections and for yieldingly securing the same in closed positions.

My invention also includes various novel features of construction, which are herein-after particularly described and pointed out in the claims.

In the drawings, Figure 1 is a side elevation of my improved casting machine; Fig. 2 is a plan view thereof; Fig. 3 is an end elevation of the same; Fig. 4 is an end elevation in detail of a mold and illustrates the carriage for said mold and mechanism for shifting the movable mold sections; Fig. 5 is a plan view thereof; Fig. 6 is a side elevation of the same; Fig. 7 is a side elevation in detail of the rack employed in opening the molds; Fig. 8 is a sectional view taken on the line 8-8 of Fig. 7; Fig. 9 is a side elevation of the rack employed in closing the molds, and Fig. 10 is an end elevation thereof.

Referring to the drawings, and particularly to Fig. 1, it will be seen that my invention consists primarily of a frame A, an endless double rail track B mounted on said frame, a series of carriages C with separable molds D thereon, adapted to travel upon said track B, a cooling tank E on the frame through which said carriages pass, an opening device F for said molds and a closing device G therefor.

The frame A consists of channel irons and angle irons, suitably braced to form a rigid structure. The water tank E is supported near one end of the frame and a filling platform 11 is arranged at the other end thereof, for workmen whose duty it is to fill the passing molds D with molten metal. A hopper 12 is also carried by the frame A and is arranged between the tank E and filling platform 11 and beneath the upper run of the track B, said hopper being employed to convey from the machine the molded product discharged from said molds.

The rails 13 of the track B are formed of angle irons, the outer flanges thereof projecting upwardly to retain the wheels 14 of the traveling carriages C upon the horizontal flanges of said rails. This track B comprises an upper and lower set of rails 75 which are bent at their ends, the lower set over-reaching the upper set of rails, to turn the mold carriages C and direct the same from one set of rails to the other.

The upper run of the track dips into the water tank E and a curved guide 15 is provided for each rail thereof to retain the wheels 14 of the mold carriages C upon said rails as they pass over the depressed portion of said track.

The mold carriages C are identical, (see Figs. 4, 5 and 6) each including a pair of side bars 16 and 17, joined at their ends by shafts 18, having wheels 14 revolvably mounted upon the opposite ends thereof. 90 The side bars 16 and 17 of the carriage are each supplied with a lug 19 depending therefrom, said lugs being secured to separate endless chains 20 extending around the frame. These chains pass over idler 95 sprocket wheels 21 mounted upon a shaft 22 at one end of the frame and also over driving sprocket wheels 23 on a shaft 24 at the other end of the frame, said shaft being connected by gear wheels 25 and 26 with a power shaft 27 upon which a power pulley 28 is secured.

An upright separable mold D is furnished for each carriage and consists of a stationary mold member 29 and a movable 105 mold member 30. Said mold members 29 and 30 are formed respectively with bearings 31 and 32 at their sides which receive the shafts 18 of the carriage. The mold member 29 is fixed upon said shafts 18 by 110

set screws 33 threaded in the bearings 31 while the second mold member 30 is slideable upon said shafts.

Means for shifting the mold member 30 5 and for yieldingly retaining the mold members in closed relation are provided. A screw 34 is mounted transversely in the bar 17 of each carriage and is formed with an annular shoulder 35 at its inner end and 10 supplied with a gear wheel 36 at the outer end thereof. Said screw is threaded in a nut 37 removably inserted in a recess 38 formed in said carriage bar 17. A bowed spring bar 39 is slidably connected at its ends to the 15 upper and lower portion of the movable mold member 30 by U-shaped clips 40 secured thereto and a split block 41 is secured at the middle of said spring bar, said block being perforated to receive the inner end of 20 the screw 34 and formed with an annular shoulder 42 adapted to engage the annular flange 35 on said screw and revolvably secure said spring and screw. The turning of the screw 34 in one direction draws the mold 25 member 30 away from the mold member 29, thereby opening the mold, and the reverse turning of said screw thrusts said mold member 30 in the opposite direction, thus closing the mold. The spring bar 39 forms 30 a yielding connection between the screw and movable mold member 30 and when the inner face of the movable mold member 30 strikes the inner face of the stationary mold member 29, said spring bar yields to permit 35 the further turning of the screw.

A mold opening device F is arranged at the top of the frame A between the filling end thereof and the hopper 12 to open the molds after the metal therein has set, and a 40 mold closing device G is located near the bottom of the frame to close the passing molds on the lower run of the track. The mold opening device F comprises a rack 43 secured to the frame and a yielding keeper 44 above said rack. This rack is arranged 45 in the path of the gear wheels 36 to engage on the lower side of said wheels and turn the same to open the mold as the carriages pass said rack. The keeper 44 is suspended horizontally above the rack 43 on bolts 45 slideable in supports 46 secured to the frame. Coiled springs 47 wound around said bolts and interposed between said supports and keeper yieldingly depress said keeper. 50 When the gear wheels 36 reach the rack 43 they pass beneath the keeper 44 and raise it slightly against the action of the springs 47, said keeper yieldingly retaining said gear wheels 36 in mesh with the rack 43, but permitting the same to rise and slide over the teeth of the rack in the event that the screws 34 will not turn, thus preventing the breakage of parts.

The mold closing device G consists of a 55 stationary rack 48 and a swinging rack 49.

Said racks are arranged in the path of the gear wheels 36, to mesh beneath and turn said wheels in a direction to close the molds. A coiled spring 50 bears upward on the lower side of the free end of the swinging 70 rack 49 and presses the same against the gear wheels 36.

In operation, the pulley 28 is turned by power to slowly advance the mold carriages C upon the frame A. Workmen standing 75 upon the platform 11 fill the passing molds D, on the upper run of the track, with molten metal. The filled molds move a considerable distance toward the rack 43 and upon reaching it are opened by the turning of the 80 gear wheels 36 as they mesh with said rack. The molded product, having congealed before the molds are opened, falls from said molds into the hopper 12 which permits it to slide by gravity from the machine. The 85 mold carriages C are then partially cooled by passing through the tank E containing water. As they advance over the driving sprocket wheels 23 said mold carriages are 90 transferred from the upper set of rails constituting the track to the lower set. The partly cooled molds D are dried by the residue of heat retained therein while slowly passing over the lower run of the track, after which said molds are closed as they 95 pass the racks 48 and 49. The gear wheels 36 first engage the stationary rack 48 which is of sufficient length to close or nearly close the molds, then pass over the upwardly pressed swinging rack 49. When the spring 100 bars 39 are compressed considerably, thus tightly closing the molds, the gear wheels 36 are hard to turn and instead of meshing properly with the teeth of the swinging rack 49 they depress said rack and slide over it. 105 Thus it will be seen that the rack 49 turns a gear 36 above it and completes the closing of a mold if it is open, but if it is tightly closed, said rack is tilted downward, thereby unmeshing the gear and rack and avoiding 110 injury to both. In passing around the idler sprocket wheels 21, the mold carriages are transferred from the lower set of rails to the upper set, where they are refilled. It will be noted that the spring bars 39 permit 115 the expansion of the molds when they are filled and thereby prevent damage to the molded product.

Having described my invention, what I claim as new and desire to protect by Letters Patent, is:

1. In a casting-machine, a frame, an endless track on said frame, a series of carriages adapted to travel on said track, means for moving the carriages, a separable mold on each carriage, said molds being adapted to be filled at one end of the frame, means to open the molds at a substantial distance from the filling point to discharge the contents thereof, a tank adapted to contain 120

water, or other cooling fluid, said track being depressed in said tank to conduct the carriages therethrough and cool the then open molds, and means for thereafter closing said 5 molds at a substantial distance from said tank.

2. In a casting-machine, a frame, an endless track on said frame, a series of carriages mounted on said track, a separable mold on 10 each carriage comprising a pair of mold members, a screw in each carriage connected with one mold member and supplied with a gear-wheel, racks on said frame arranged to engage and turn the gear-wheels to open 15 and close the molds, and resilient means to yieldingly hold the members together when the molds are closed.

3. In a casting-machine, a frame, a mold carriage movable on said frame, a mold on 20 said carriage comprising a plurality of separable members, mechanism on the carriage to open and close the mold in its travel, and resilient means adapted to yieldingly hold said members together when the mold is 25 closed.

4. In a casting machine, a frame, an endless track on said frame, a series of carriages mounted on said track, a separable mold on each carriage comprising a stationary and a movable mold member, a screw in each carriage connected at its inner end to said movable mold member and supplied at its outer end with a gear wheel, and racks on said frame arranged to engage and turn 35 said gear wheels, whereby the movable mold members are shifted to open and close said molds.

5. In a casting machine, a frame, an endless track on said frame, a series of carriages 40 mounted on said track, a separable mold on each carriage comprising a stationary and movable mold member, a screw in each carriage yieldingly connected at its inner end to said movable mold member and supplied 45 at its outer end with a gear wheel, and racks on said frame arranged to engage and turn said gear wheels, whereby the movable mold members are shifted to open and close said molds.

50 6. In a casting machine, a frame, an endless track on said frame, a series of carriages mounted on said track, a separable mold on each carriage comprising a stationary and movable mold member, a screw threaded 55 transversely in each carriage, a bowed spring bar slidably secured at its ends upon the outer side of the movable mold member, the inner end of said screw being revolubly connected with said spring, a gear wheel on the

60 outer end of said screw and racks on said frame arranged to engage and turn said gear wheels whereby the movable mold members are shifted to open and close said molds.

65 7. In a casting machine, a frame, an endless track on said frame, a series of carriages

mounted on said track, a pair of endless chains connecting said carriages, driving and idler sprocket wheels on said frame over which said chains pass, a mold on each carriage comprising a stationary and a movable 70 mold member, a screw threaded transversely in each carriage, connected at its inner end to said movable mold member and supplied at its outer end with a gear wheel, a rack on said frame arranged to engage and turn said 75 gear wheels whereby the movable mold members are shifted to open said molds, a keeper arranged to press upon said gear wheels and yieldingly retain the same in mesh with said rack and a second rack arranged to engage and turn said gear wheels to close the molds.

8. In a casting machine, a frame, an endless track on said frame, a series of carriages mounted on said track, a pair of endless 85 chains connecting said carriages, driving and idler sprocket wheels on said frame over which said chains pass, a mold on each carriage comprising a stationary and a movable mold member, a screw threaded trans- 90 versely in each carriage, connected at its inner end to said movable mold member and supplied at its outer end with a gear wheel, a rack on said frame arranged to engage and turn said gear wheels, whereby the movable 95 mold members are shifted to open the molds, a keeper arranged to press upon said gear wheels and yieldingly retain the same in mesh with said rack and a second rack arranged to engage and turn said gear 100 wheels to close the molds, said second rack being supplied with a yielding section adapted to be depressed by said gear wheels in the event that the same fail to turn.

9. In a casting machine, a frame, a cooling tank containing water located near one end of the frame, an endless track extending from one end of the frame to the other, said track consisting of an upper and lower set of rails overlapped at their ends, said upper set of rails passing through said tank, a series of carriages movably mounted on said track, means for driving said carriages, a mold on each carriage consisting of a stationary mold member and a movable mold member, said molds being adapted to be filled at the end of the frame opposite the tank and moved toward said tank, a hopper arranged beneath the upper set of rails and between the tank and filling end of the 110 frame, means above the hopper for opening the molds to release the contents thereof into said hopper and means for closing the molds.

10. In a casting machine, a frame, an endless track on said frame, a plurality of carriages, power driven chains connecting said carriages in an endless series, each carriage comprising a pair of side bars, a pair of shafts passing transversely through said side bars and wheels mounted on the outer ends 125 130

of said shafts and adapted to travel on said track, a stationary mold member supported between said shafts and secured thereto, a movable mold member supported between 5 and slidable on said shafts, a screw threaded transversely in one bar of each carriage, said screw being connected at its inner end to said movable mold member and supplied at its outer end with a gear wheel, and racks 10 on said frame arranged to engage and turn

said gear wheels, whereby the movable mold members are shifted to open and close said molds.

In testimony whereof, I have signed my name to this specification in the presence of 15 two subscribing witnesses.

CHARLES HENRY LISTER.
